FIG. 14

FIG. 1 is a perspective view of an educational toy showing my new design with a portion thereof in a raised position and parts removed therefrom;

FIG. 2 is a side elevation thereof;

FIG. 3 is a front elevation thereof;

FIG. 4 is a top plan view thereof;

FIG. 5 is a rear elevation thereof;

FIG. 6 is a front elevation thereof with a portion of the toy in raised position;

FIG. 7 is a side elevation thereof as shown in FIG. 6;

FIG. 8 is a perspective view of modified form of the design shown in FIG. 1, wherein a flat top has been substituted for the roof portion, the wheels have been omitted, and apertures substituted on the top and sides;

FIG. 9 is a perspective view thereof as shown in FIG. 8 with the lace undone and the tongue in open position;

FIG. 10 is a side elevation of view thereof as shown in FIG. 8;

FIG. 11 is a side elevation of view of the opposite side thereof as shown in FIG. 8;

FIG. 12 is a top plan view thereof as shown in FIG. 8;

FIG. 13 is a front elevation of view thereof as shown in FIG. 8, and

FIG. 14 is a rear elevation of view thereof as shown in FIG. 8.

The dominant features of my design reside in the portions shown in full lines. The broken-line figures seen in FIGS. 3, 6, 7, 8, 9, and 13 are for illustrative purposes only.

I claim:

The ornamental design for an educational toy, substantially as shown and described.
